UNITED STATES PATENT OFFICE.

CHARLES M. CLARKE, OF SEWICKLEY, PENNSYLVANIA.

DISCHARGE-CHUTE FOR CONCRETE-MIXERS.

1,333,705.

Specification of Letters Patent. Patented Mar. 16, 1920.

Application filed January 31, 1918. Serial No. 214,574.

To all whom it may concern:

Be it known that I, CHARLES M. CLARKE, a citizen of the United States, residing at Sewickley, in the county of Allegheny and 5 State of Pennsylvania have invented certain new and useful Improvements in Discharge-Chutes for Concrete-Mixers, of which the following is a specification.

My invention refers to improvements in 10 concrete mixers of the rotary drum type, and particularly to a discharge chute therefor. It has in view to provide a discharge chute which is capable of being made operative to conduct the mixture out of the 15 mixer, or inoperative, by closing and opening the sides of a chute.

In the drawings I have shown the invention as embodied with a typical construction 20 of mixing drum, it being understood that the improved discharge chute is not necessarily dependent on the interior construction of the mixer, as to its feeding or charging and mixing elements.

In the drawings, which show preferred 25 forms of the invention,

Figure 1 is a view in elevation of the discharge end of a mixer provided with my invention;

Fig. 2 is a vertical sectional view on the 30 line II, II of Fig. 1;

Fig. 3 is a view similar to Fig. 1 showing the adjustable chute members in open position, the outer chute being removed;

Fig. 4 is a similar detail view, showing a 35 modified construction.

In the drawings 2 is the mixer drum rotatably mounted on rollers 3 and having an annular rack 4 for engagement by a driving pinion all of well known construction.

40 Mixers of this type are usually provided at each end with a partly closing head or flange 5, 6, respectively, each open at the center for introduction of the raw material and removal of the mixture respectively.

45 The raw material may be introduced by a charging chute 7 and is carried inwardly of the drum by any advancing and mixing elements, as a series of individual blades 8, 9, or the like.

50 These elements are of any desired or suitable number, and their depth, length, inclination, or other characteristics may be varied or modified to suit the requirements or to conform to the standard construction 55 of the particular machine with which my

improved discharge chute is incorporated, without in any way affecting its construction or operation.

The purpose in view in mixers of the rotary drum type is to thoroughly mix the sand, gravel, cement, and water, and to advance the same toward the discharge end, so that a "batch" may be taken from the machine as needed from time to time. Ordinarily a wheelbarrow load is desired at 65 each discharge.

Various kinds of discharge devices have been used, either attached to and revolving with the drum or mounted independent thereof, and arranged to discharge the mixture outwardly or to return it back to the interior, as with the pivotal closed-bottom chute, or otherwise.

My discharge chute utilizes a pair of opening and closing sides 10, 10, the upper edges of which are hinged to supporting rods or pins 11, 11, these parts extending inwardly of the open rear end of the drum. The opening and closing or adjustable chute members preferably form an extension of a 75 stationary normally closed chute 12 leading outwardly of the drum and terminating there beyond at a position suitable for discharge into a barrow or the like. As shown, the compound chute is V-shaped, in which 80 case the movable sides 10 will hang vertically when open, as in Fig. 3, so as not to interfere with the free falling down of the mixture within the drum. When closed, as in Fig. 1, these sides form a trough and 85 conform generally to the stationary trough or chute 12, and operate to collect a portion of the mixture as it is carried around by the rear portions of the blades, or the pockets 90 13 thereof, and discharge it by gravity down 95 through the sloping passageway and onto the discharge chute 12.

In Fig. 4 I show a modified construction in which the adjustable sides 10^a are curved transversely, so that when together, they 100 form practically a semi-circular trough. When open the sides hang in the positions shown in dotted lines.

The adjustable chute sides 10 may be actuated by any suitable operating means, as a 105 lever 14 pivoted by a shaft 15 in a bearing or bearings 16 at one or both ends of the machine.

An advantage in having a lever at each end of the machine, as shown, is that the 110

discharge mechanism can be operated from either end, in which case the levers should be secured to the shaft 15.

The lever 14 at the discharge end of the machine is pivotally connected by links 17, 17 at each side of its pivotal bearing 16 by their inner ends, and to arms 18 of the hinged sides 10, at their outer ends by pivotal connections 19. If desired, a spring 20 may be connected to lever 14 at 21 and to a connection 22 vertically below the shaft bearing. By this means the throw of the lever beyond the dead center and the opening or closing of the sides 10 may be assisted. In the construction shown, the non-swinging end of the spring is secured to a portion of the bracket 23 which provides the pivotal bearing 16, said bracket being rigidly mounted on outer supporting framework as by bolts 23'. However, any other well known means may be employed, if desired, for fixedly holding the lever and the chute sides in open or closed position, as by the usual segment and lever actuated locking key in common use with railroad switch levers.

The relative length of the sides 10 as to the permanent chute 12, and other features of the construction, may be made to suit the design, conditions of use, etc. of the machine as a whole. An advantage in the closed bottom delivery chute section 12 is that any leakage outside of the machine is avoided, and when the sides 10 are opened, any adhering concrete will be returned to the interior of the machine by gravity.

The construction and operation of the device will be readily understood and appreciated by all those accustomed to this class of machines. While open the sides 10 hang pendently without effect, but when they are closed together, they immediately collect the falling mixture and deflect it outwardly of the machine for as long a time as desired, and the discharge operation may be discontinued at will by mere operation of the lever.

What I claim is:—

1. In combination with a rotary concrete mixer drum having a separate fixedly mounted inclined discharge chute leading from the mixer to the exterior thereof, a pair of similarly inclined hinged sides extending

from the inner end of said chute into the mixer interior at its discharge end portion, means for opening and closing the hinged sides together, and means independent of the mixer drum providing hinge supports for said sides.

2. In combination with a rotary concrete mixer drum having a separate fixedly mounted inclined discharge chute leading from the mixer to the exterior thereof, a pair of similarly inclined hinged sides extending from the inner end of said chute into the mixer interior at its discharge end portion, means independent of the mixer drum providing hinge supports for said sides, a pivoted operating lever and a support therefor, and means connecting the lever and the hinged sides whereby they may be opened and closed together.

3. In combination with a rotary concrete mixer drum having a separate fixedly mounted inclined discharge chute leading from the mixer to the exterior thereof, a pair of similarly inclined hinged sides extending from the inner end of said chute into the mixer interior at its discharge end portion, means independent of the mixer drum providing hinge supports for said side, a pivoted operating lever and a support therefor, and links connecting the lever at opposite sides of its pivotal mounting with pivotal bearings on the hinged sides whereby they may be opened and closed together.

4. In combination with a rotary concrete mixer drum having a separate fixedly mounted inclined discharge chute leading from the mixer to the exterior thereof, a pair of similarly inclined hinged sides extending from the inner end of said chute into the mixer interior at its discharge end portion, means independent of the mixer drum providing hinged supports for said side, a pivoted operating lever and a support therefor, means connecting the lever and the hinged sides whereby they may be opened and closed together, and a spring connected with the lever and its support adapted to hold the lever and the hinged sides in open or closed position.

In testimony whereof I hereunto affix my signature.

CHARLES M. CLARKE.
